FRAME FOR MULTIPLE-PANE WINDOW SASHES

Raphaël Lemyre, Sorel, Quebec, Canada

Application July 13, 1946, Serial No. 683,535
In Canada July 26, 1945

6 Claims. (Cl. 20—56.5)

1

The present invention pertains to a novel frame for multiple-pane window sashes. The principal object of the invention is to provide a frame that seals and insulates the spaces between the panes so that it is no longer necessary to provide a two-part or dual sash in order to obtain an enclosed insulating space.

Another object of the invention is to provide a sealed sash of the character described which is especially suitable for any kind of vehicle such as railroad cars, airplanes, motor cars, dirigibles, etc., and the like to insure good visibility regardless of temperature variations on both sides of the window. Another object of the invention is to provide a frame that holds a plurality of panes of glass or transparent plastic material with an air tight seal.

Still another object of the invention is to provide a frame for multiple panes of the character described in which it is necessary to clean only the outer surfaces of the respective panes due to the fact that the inner surfaces are protected from accumulation of dirt thereon.

Still another object of the invention is to provide a device of the character described which is simple and inexpensive in construction and easily assembled.

In the accomplishment of these objects, the invention comprises a single frame in which several panes are mounted. A tight seal for the space or spaces between the panes is formed by inserting the edges of the panes first in relatively solid resilient strips of natural rubber, synthetic rubber or equivalent material. In order to seal the spaces, a means is provided for clamping the resilient strips on their sides and thus against the individual panes.

The last named means is incorporated in the moulding strips engaging the lateral surfaces of the resilient strips. Outward of the resilient strips, the binding strips are spaced apart and are formed with outwardly diverging inner surfaces. Between each pair of opposed moulding strips is inserted a binding strip with its longitudinal edges rounded and the moulding strips pivotally mounted thereon. A wedge inserted between the opposed moulding strips can be adjusted to rock the latter on the intervening binding strips, thereby compressing the moulding strips in the inserted resilient strips and sealing the latter tightly against the panes. The wedge is in the form of a channel having outward or inward diverging sides and is attached by screws to the corresponding binding strip. The described clamping action on the resilient strips is obtained by tightening the screws.

2

As well known in the art, a sealed air space between window panes constitutes a good insulator. If desired, the space may be evacuated and filled with a gas that is a still better insulator of heat. It is evident that moisture and dirt cannot collect on the inner surfaces of the panes because of the tight seal. Consequently, only the outer surfaces need be washed. If insufficient, in particular cases, a thin metal sheet could

10 cover the rubber strip between the window panes.

The invention is fully disclosed by way of example in the following description and in the accompanying drawings in which:

Figure 1 is a cross section of a sash frame for 15 multiple window panes;

Figure 2 is a detail elevation thereof, partly broken away;

Figure 3 is a perspective view of a corner;

Figure 4 is a section similar to Figure 1, showing 20 also the stationary frame;

Figure 5 is a section on the line 5—5 of Figure 3, and

Figure 6 is a section of a modified construction.

25 Reference to these views will now be made by use of like characters which are employed to designate corresponding parts throughout.

In Figures 1, 2 and 4 are shown two panes 1 spaced apart and having their edges received in 30 grooves or slots 2 formed in a surrounding strip 3 consisting of a solid resilient material such as natural or synthetic rubber. The strip is in four sections, assuming that the panes are quadrilateral, and the corners are mitered as shown in Figures 2 and 3. The longitudinal outer edges of the strips 3 are rabbeted at 4, and the adjacent moulding strips 5 at opposite sides of the strips 3 are formed with ribs 5a received in the grooves 4.

40 A binding strip 6 is laid between the members 5 in engagement with the outer transverse surface of each strip 3. The edges 7 of the members 6 are rounded and received in correspondingly shaped grooves 8 in the strips 5. The member 45 6 unites the adjacent moulding strips 5 and serves as a pivotal support for them for a purpose that will presently be described.

Outwardly of the members 6 the strips 5 are bevelled at 9 on their inner surfaces so that the 50 opposite surfaces diverge outwardly. The opposed surfaces are engaged by the inclined flanges 9 of an inserted U-shaped wedge member 10. At suitable uniform distances, tightening screws 11 are passed through each member into the adjacent strip 6. On tightening the screws 11, the inclined surfaces 9 are spread apart, inasmuch

as the strips 5 rock on the ends of the members 6 as set forth above. The inner edges of the members 5 are compressed against the sides of the respective strips 3, thereby forming tight seals around the edges of the panes 1. Because of the tightness, there is obtained an air tight insulating space between the panes 1, and this space may be filled with an insulating gas if desired.

The structure thus far described is enclosed in a frame, as shown in Figure 4, consisting of a pair of side members 12 united at a suitable lap joint 13 and secured by screws or nails 14. The ends of the strips 5 are mitered as shown in Figure 2 except at the extreme outer corners where they are cut and fitted on a joint line 15 parallel to one of the outer edges and fastened together by a dowel 16 as shown in Figures 2 and 3. Screws 17 are passed through the frame members 12 into the strips 5, and the inner surfaces of the members 12 are flared slightly outwardly at 18 to permit the aforementioned rocking movement of the members 5.

In the modification shown in Figure 6 the resilient strips 3' are wider than shown in Figures 1 and 4 and are formed with four grooves 2' to receive the edges of four panes 1'. The binding strip 6' and the spreader 10' are likewise wider in order to engage the lateral strips 5'.

Although specific embodiments of the invention have been illustrated and described, it will be understood that various alterations in the details of construction may be made without departing from the scope of the invention as indicated by the appended claims.

What I claim as my invention is:

1. A sash frame comprising elongated resilient strips forming an enclosure for a window and having spaced grooves in their inner edges, spaced panes having their edges received in said grooves, moulding strips engaging the lateral surfaces of said resilient strips, binding strips inserted respectively between said opposed moulding strips and engaging the outer surfaces of said resilient strips, said moulding strips being pivotally attached to said binding strips, and means for rocking said moulding strips on said binding strips to tighten said moulding strips against said resilient strips.

2. A sash frame comprising elongated resilient strips forming an enclosure for a window and having spaced grooves in their inner edges, spaced panes having their edges received in said grooves, moulding strips engaging the lateral surfaces of said resilient strips, binding strips inserted respectively between opposed moulding strips and engaging the outer surfaces of said resilient strips, said moulding strips being pivotally attached to said binding strips, wedging members inserted between said opposed moulding strips, and screws passed through said wedging members into the corresponding binding strips for rocking said moulding strips on said binding strips to tighten said moulding strips against said resilient strips.

3. A sash frame comprising elongated resilient strips forming an enclosure for a window and having spaced grooves in their inner edges, spaced panes having their edges received in said grooves, moulding strips engaging the lateral surfaces of said resilient strips, binding strips inserted re-

spectively between said opposed moulding strips and engaging the outer surfaces of said resilient strips, said moulding strips being pivotally attached to said binding strips, the inner surfaces of opposed moulding strips diverging outwardly, wedging members inserted between said opposed moulding strips and screws passed through said wedging members into the corresponding binding strips for rocking said moulding strips on said binding strips to tighten said moulding strips against said resilient strips.

4. A sash frame comprising elongated resilient strips forming an enclosure for a window and having spaced grooves in their inner edges, spaced panes having their edges received in said grooves, moulding strips engaging the lateral surfaces of said resilient strips, binding strips inserted respectively between said opposed moulding strips and engaging the outer surfaces of said resilient strips, said moulding strips being pivotally attached to said binding strips, the inner surfaces of opposed moulding strips diverging outwardly, a U-shaped wedging member inserted between said pair of opposed moulding strips and having outwardly diverging flanges engaging said diverging surfaces, and screws passed through said wedging members into the corresponding binding strips for rocking, said moulding strips on said binding strips to tighten said moulding strips against said resilient strips.

5. A sash frame comprising elongated resilient strips forming an enclosure for a window and having spaced grooves in their inner edges, spaced panes having their edges received in said grooves, moulding strips engaging the lateral surfaces of said resilient strips, binding strips inserted respectively between said opposed moulding strips and engaging the outer surfaces of said resilient strips and having rounded edges, said moulding strips being pivotally fitted on said edges, and means for rocking said moulding strips on said binding strips to tighten said moulding strips against said resilient strips.

6. A sash frame comprising elongated resilient strips forming an enclosure for a window and having spaced grooves in their inner edges, spaced panes having their edges received in said grooves, moulding strips engaging the lateral surfaces of said resilient strips, binding strips inserted respectively between said opposed moulding strips and engaging the outer surfaces of said resilient strips, said moulding strips being pivotally attached to said binding strips, and means for rocking said moulding strips on said binding strips to tighten said moulding strips against said resilient strips, and a channelled frame having a U-shaped cross-section enclosing said moulding strips, the channel of said frame being shaped to permit the rocking movement of said moulding strips.
